UNITED STATES PATENT OFFICE.

NICHOLAS GLAB, OF DUBUQUE, IOWA, ASSIGNOR TO FRANK C. H. STRASBURGER, OF CHICAGO, ILLINOIS.

BOTTLE-FILLING MACHINE.

SPECIFICATION forming part of Letters Patent No. 732,065, dated June 30, 1903.

Application filed November 1, 1902. Serial No. 129,774. (No model.)

To all whom it may concern:

Be it known that I, NICHOLAS GLAB, a citizen of the United States, residing at Dubuque, in the county of Dubuque and State of Iowa, ⁵ have invented certain new and useful Improvements in Bottle-Filling Machines, of which the following is a specification.

This invention relates to bottle-filling machines, and has for its object to provide a ¹⁰ simple and automatically-operating machine for rapidly filling bottles with liquid.

The invention also has in view to provide a machine of this character with valve mechanism of novel and improved construction ¹⁵ which will prevent waste of liquid and with means for permitting the escape of air displaced by the liquid as the bottle is being filled.

The invention has other objects in view, ²⁰ which will fully appear hereinafter in the detailed description hereof and in the claims.

In the accompanying drawings, Figure 1 is a central sectional view of a machine embodying my invention, two filling-tubes and ²⁵ valves only being shown to avoid confusion. Fig. 2 is a sectional view on the line 2-2 of Fig. 1, showing the openings in the tank for receiving the valve mechanisms and some of the valves in place. Fig. 3 is a top plan view ³⁰ of the cam. Fig. 4 is a bottom plan view of the bearing-hanger for the actuating-levers. Fig. 5 is a detail view. Fig. 6 is an enlarged top plan view of one of the valve mechanisms. Figs. 7 and 8 are sectional views on the lines 7-7 and 8-8, respectively, of Fig. 6. Fig. 9 is a bottom plan view on the line 9-9 of ³⁵ Fig. 7. Fig. 10 is a detail view of the valve-disk for the air-vent.

Like numerals of reference indicate corresponding parts in the several figures of the drawings, and referring thereto, 12 is a base of suitable character, and 13 is a driving-shaft journaled in bearings 14 and carrying the belt-pulleys 15 and a worm 16, which is ⁴⁰ arranged to mesh with the worm-gear 17 on the vertical driven shaft 18. A plate 19 is fastened on the driven shaft above the base and carries at its periphery a number of arms 20, each of which is bored to receive and guide ⁴⁵ the stem 21 of a bottle-rest 22. The bottle-

rest is provided on its under side with a socket 23 to receive the upper end of the stem, and a spring 24 is arranged in said socket above the stem to permit the rest to yield, and thus provide for variations in the height of the ⁵⁵ bottles. The bottle-rest is thrust upward by means of a crank-lever, which is preferably in the form of an elbow and has its long arm 25 connected by a link 26 with the lower end of the stem and its short arm 27 provided ⁶⁰ with an antifriction-roller 28, arranged to travel around a cam 29, rigid with the base and preferably shaped like a saucer, Fig. 3. The actuating-lever is carried by a support 30, which is rigid with the driven shaft and ⁶⁵ is preferably made integral with the guide carrying plate 19. This support is provided at the bottom, Fig. 4, with a slot 31 to receive the actuating-lever and bearings 32 for the stub-axles 33 of said lever. These bearings ⁷⁰ are formed in the construction illustrated in the drawings by cutting out the support on the under side, so that the axles of the lever may be slipped upward into place from below and there secured by blocks 34. ⁷⁵

The machine may be constructed to accommodate at one time any number of bottles, and the construction illustrated in the drawings is made to receive twenty-four bottles; but in Fig. 1 I have for clearer illustration ⁸⁰ shown but two sets of the filling mechanism, one bottle being filled and the other bottle filled and ready to be removed or empty and placed on the rest, as the case may be.

A tank 35 is mounted on the upper end of ⁸⁵ the driven shaft and travels therewith. This tank is provided with a removable cover 36, which is secured in place by means of thumb-screws 37, so that the tank can be made practically air-tight. A feed-pipe 38 is arranged ⁹⁰ in a stuffing-box 39 in the cover of the tank, and this feed-pipe is connected to a source of supply and discharges into a curved spout 40, which is rigidly secured within the tank. To control and regulate the supply of liquid ⁹⁵ in the tank, I provide a float 41 and a valve 42, so arranged that when the liquid has reached a predetermined level in the tank the valve 42 will be closed by the float, and the subsequent increase of pressure within the ¹⁰⁰

tank will sooner or later, depending upon the pressure at the supply, stop the flow of liquid into the tank.

Referring particularly to Sheet 3 of the drawings, the valve mechanism comprises a body 43, which is screwed into an opening 44, Fig. 2, in the bottom of the tank and is provided with a central bore 45, into the lower end of which the filling-tube 46 is screwed.

- 10 On the upper face of the body 43 and around the opening 45 is a rubber gasket 47, which forms a seat for the valve 48, and this valve is fastened on the rods 49, which also carry at the lower end the head 50. A spring 51 is arranged on each of the rods 49 and bears at its lower end against the head 50 and at its upper end against a plug 52, which works in an opening 53 in the head and against the packing 54. The springs normally hold the valve closed, and at the same time they press the plugs tightly against the packing, and thus prevent the escape of liquid from the tank through the openings in which the rods work. The head 50 is provided with a central bore 55 to receive the filling-tube 46, and it has a rubber gasket 56 on its upper face and a seat 57 on its lower face to receive the mouth of the bottle, the outer face 58 of this seat converging inwardly, as shown in Fig. 7, to provide an effective closure with the bottle. The parts are constructed and arranged so that in their normal position when the valve is closed the head 50 will be held below the body 43; but when the bottle is carried upward into position against the seat 58 as shown at the left of Fig. 1, the head, and with it the connecting-rods and valve, will be forced upward to unseat the valve, and thus permit the liquid in the tank to flow
- 20 down through the filling-tube and into the bottle. The valve remains open until the actuating-lever reaches the cut-out portion of the cam, whereupon the bottle and its supporting mechanism descend, and the springs 51 simultaneously close the valve.

In order that the air may escape from the bottle while it is being filled, I provide a vent which comprises a passage 59 through the body, which opens at its lower end in the space between the body and head 50, inclosed by the gasket 56 when the filling-valve is open, and at the top in a chamber 60. This chamber contains a valve of suitable character, which may consist of a loose disk 61, Fig. 10, provided with notches 62 on its periphery and grooves 63 on its upper face and held in the chamber by a hollow screw-plug 64, to which is connected a pipe 65 to discharge the air above the liquid-level in the tank. When the bottle has been clamped in place and the liquid begins to flow therein, the air will be forced out and up around the outside of the filling-tube into the space between the head and body inclosed by the gasket 56 and out through the passage 59 into the chamber 60, where the pressure of air will raise the valve 61, so that the air can flow out through the

notches and grooves in the valve-disk and the tube 65 into the tank. Just as soon as the pressure of the air is insufficient to raise the valve 61 it will drop back and close the passage 59, so as to raise the pressure in the tank. I provide grooves 66 in the wall of the opening 55 in the head to enable the air to pass up through the head and to the passage 59.

It will of course be understood that for each bottle on the machine there is an independent mechanism for raising the bottle and an independent valve mechanism, and therefore a machine can be constructed to accommodate at one time as many bottles as may be desired. The cam is preferably timed so that the bottle will descend immediately or at least shortly after it is filled, and thus give the operator plenty of time to remove the bottles and insert new ones in place. This arrangement will also permit the operator to remove several filled bottles at a time, or if the machine is traveling at a comparatively high rate of speed one boy may insert the bottles while another boy removes them. As the bottle is tightly clamped against the head 50, so as to prevent the escape of liquid, it does not matter particularly how long the filling-valve remains open, and therefore the machine may be constructed to accommodate a large number of bottles at the same time and operate rapidly, so that the filling operation may be conducted at considerable speed.

My invention may be embodied in machines which differ more or less in construction from the one illustrated in the drawings and heretofore described, but without departing from the essential features and principles, and I would, therefore, have it understood that I reserve the right to make all changes which may be fairly considered to come within the purview of the invention.

The machine operates automatically, and the bottles may be inserted and removed by unskilled boys. The construction is such that no loss of liquid will occur if the operator fails to insert a bottle on each filling-tube, as the valve is not opened until the bottle is clamped in place, nor will the liquid which remains in the tube escape when the bottle is removed by reason of the pressure of air at the lower end of the tube and the fact that the filling-valve closes the upper end thereof. I prefer to contract the lower end of the filling-tube, as shown in Fig. 1. The construction is preferably such that the operator will of necessity arrange the mouth of the bottle on the lower end of the filling-tube to prevent the bottle from slipping off and form a guide therefor when the bottle is elevated to insure its being seated properly against the head.

Having thus fully described my invention, what I claim, and desire to secure by Letters Patent, is—

1. A bottle-filling machine comprising a liquid-tank, a filling-valve, a rest for the bot-

tle, a lever swinging in a vertical plane, means for revolving the tank, bottle-rest and lever, and a horizontally-disposed fixed cam actuating the lever to cause the bottle to open the 5 valve and hold it open while the bottle is being filled.

2. A bottle-filling machine comprising a liquid-tank, a filling-valve, a rest for the bottle, an elbow-lever, means for revolving the 10 tank, bottle-rest and lever, and a fixed cam actuating said lever to lift the bottle-rest a distance approximately equal to the height of the bottle and force the bottle against and open the valve and hold the valve open while 15 the bottle is being filled and then permit the bottle to descend and the valve to close.

3. A bottle-filling machine comprising a liquid-tank, a filling-valve in the tank, a rest for the bottle, means for revolving the tank 20 and bottle-rest, a fixed cam, and a pivoted actuating-lever revolving with the tank and bottle-rest and riding against said cam, and adapted to raise and lower the bottle-rest.

4. A bottle-filling machine comprising a liquid-tank, a filling-valve in the tank, a rest 25 for the bottle, means for revolving the tank and bottle-rest, a fixed cam, a crank-lever revolving with the tank and bottle-rest and with one arm thereof riding against said cam, 30 and a stem supporting the bottle-rest and operated by the other arm of said lever.

5. A bottle-filling machine comprising a liquid-tank, a filling-valve in said tank, a rest for the bottle, means for revolving the tank 35 and bottle-rest, a fixed cam, a crank-lever arranged to revolve with the tank and bottle-rest and with one arm thereof riding against said cam, a stem supporting the bottle-rest, a connection between said stem and the 40 other arm of said lever, and a guide for said stem.

6. A bottle-filling machine comprising a liquid-tank, a filling-valve carried by said tank, a rest for the bottle, a stem connected 45 with the bottle-rest, a crank-lever comprising a long arm connected with the stem and a short arm, and a cam to operatively engage the short arm of the lever to raise the bottle into engagement with and to open the valve.

50 7. A bottle-filling machine comprising a liquid-tank, a filling-valve carried by said tank, a rest for the bottle, a stem connected with the bottle-rest, a crank-lever comprising a long arm and a short arm, a link connection 55 between the stem and the long arm of the lever, and a cam to operatively engage the short arm of the lever to raise the bottle into engagement with and to open the valve.

8. A bottle-filling machine comprising a liquid-tank, a filling-valve in said tank, a rest 60 for the bottle, means for revolving the tank and bottle-rest, a stem supporting the bottle-rest, a fixed cam, and a crank-lever arranged to revolve with the tank and bottle-rest and 65 having its long arm connected with the stem and its short arm operatively engaging the cam.

9. A bottle-filling machine comprising a liquid-tank, a filling-valve, a rest for the bottle, a shaft for revolving the tank and bottle-rest, a stem supporting the bottle-rest, a fixed cam, a support carried by said shaft and located adjacent to said cam, and a crank-lever pivotally carried on said support and having its long arm connected with said stem and its 70 short arm operatively engaging the cam.

10. A bottle-filling machine comprising a liquid-tank, a filling-valve, a rest for the bottle, a shaft for revolving the tank and bottle-rest, a stem supporting the bottle-rest, a fixed 75 cam, a support rigid with the shaft, a crank-lever pivotally carried by said support and having its short arm operatively engaging the cam and its long arm movably connected to said stem.

80 11. A bottle-filling machine comprising a liquid-tank, a filling-valve, a rest for the bottle, means for revolving the tank and bottle-rest, a fixed saucer-shaped cam, and a crank-lever revolving with the tank and bottle-rest 85 and riding against the periphery of said cam to raise and lower the bottle.

12. A bottle-filling machine comprising a liquid-tank and a filling-valve mechanism comprising a body, a head, a gasket on the 90 upper side of said head arranged to engage the body, a valve, and an air-passage in the body opening at the lower end thereof within the space inclosed by the gasket when in engagement with the body, and discharging into 95 the tank.

13. A bottle-filling machine comprising a liquid-tank and a filling-valve mechanism comprising a body, a head, a gasket on the 100 head arranged to engage the body, a valve connected with the head, an air-passage in the body opening at the top in a chamber in the body and at its bottom at the bottom of the body in the space inclosed by the gasket when engaging with the body, a valve in said 105 chamber, and an outlet from said chamber into the tank.

14. A bottle-filling machine comprising a liquid-tank and a filling-valve mechanism comprising a body having an opening therethrough, a filling-tube communicating with 110 said opening and carried by the body, a head provided with an opening to receive said filling-tube and a groove in the wall of said opening, a gasket on the upper face of the 115 head, a valve connected with said head and normally closing the opening in the body, an air-passage opening at its upper end into a chamber in the body and at its lower end at the bottom of the body in the space inclosed 120 by the gasket when in contact with the body, a gravity-disk valve in said chamber provided with notches in its periphery and grooves on its upper face, and a discharge from said chamber into the tank above the level of the liquid 125 therein.

15. In a machine of the character described, the combination with a driven shaft, of a tank mounted on and revolving with said

shaft, a series of filling-valves in said tank, a filling-tube communicating with each valve-opening, a bottle-rest beneath each filling-tube and revolving with the shaft and tank, 5 a crank-lever, and a cam for actuating said lever to raise and lower the bottle-rest.

16. In a machine of the character described, the combination of a liquid-tank, a series of filling-valves carried by said tank, a bottle-10 rest located beneath each of said valves, a stem supporting each bottle-rest, a guide for each stem, a stationary base, a fixed cam

mounted on said base, an elbow-lever pivotally supported between the cam and each stem and having one arm thereof connected with the stem and the other arm in operative engagement with the cam, and means for revolving the tank, the bottle-rests and stems, the guide, and the cranks. 15

NICHOLAS GLAB.
